UNITED STATES PATENT OFFICE.

FRED GIBBONS, OF YORKTON, SASKATCHEWAN, CANADA.

SAFETY-STIRRUP.

1,357,161.

Specification of Letters Patent. Patented Oct. 26, 1920.

Application filed February 7, 1919. Serial No. 275,584.

To all whom it may concern:

Be it known that I, FRED GIBBONS, a subject of the King of England, residing at Yorkton and Province of Saskatchewan, Canada, 5 have invented new and useful Improvements in Safety-Stirrups, of which the following is a specification.

The object of the invention is to provide a stirrup which will effectively and quickly 10 release the foot of a rider should the latter be thrown from his mount. To this end the invention comprises a stirrup composed of an L-shape section and two hingedly mounted sections attached to the L-shape section 15 to give the stirrup its proper form, the hingedly mounted sections being releasable and being automatically thrown back when released. The release of these hingedly mounted sections is effected by means of a 20 strap control catch mounted on the L-shape section.

The invention is illustrated and described in a specific embodiment to which, however, it is not to be restricted. The right is re- 25 served to make such changes or alterations as the actual reduction to practice may suggest, in so far as such changes or alterations are compatible in spirit with the annexed claim.

30 In the accompanying drawings:

Figure 1 is a view in front elevation of the improved stirrup.

Fig. 2 is a side elevational view looking in the direction of the arrow A in Fig. 1.

35 Fig. 3 is a side elevational view looking in the direction of the arrow B of Fig. 1.

Fig. 4 is a section on the line 4—4 of Fig. 1.

40 Fig. 5 is a section on the line 5—5 of Fig. 1.

Referring to the drawings, the stirrup is shown as representing an L-shape body element 1, the shorter leg of this element comprising the upper transverse member of the 45 stirrup and having formed therein the eye 2 for the attachment of the stirrup strap. The free end of the leg 2 is straddled by the legs 3 of the bifurcated end of the arm 4 and this arm is pivotally connected to the 50 upper arm of the member 1, a pin 5 passing through the legs 3 and loosely engaging an appropriate hole adjacent the end of the shorter leg of the body member.

55 The tread plate 5' is formed with two spaced ears 6 which straddle the lower end of the arm 4 to permit the tread plates be-

ing pivotally attached to the arm 4 which attachment is effected by means of the pin 7 set in the two ears and loosely engaging a hole in the arm 4.

At the end remote from the ears the tread plate is formed with a tongue 8 and this tongue 8 is held in a recess formed part in the long leg of the body element 1 and part in the jaw 9 which is hingedly attached at 60 the lower end of the longer leg of the body element, as indicated at 10. It will be observed in Fig. 2 that this jaw 9 is so attached to the body element and so supports the tongue that any pressure imposed upon 65 the tread plate will tend to throw the jaw open and thus release the tread plate, the hinge being in one side of the tongue to facilitate such throwing of the jaw. To preclude movement of the jaw, however, 70 except when it is necessary to release the tread plate, the upper end of a long leg of the body member has mounted thereon a spring-held catch 12 which engages a lug 13 formed at the upper end of the jaw. 75 The catch consists of a lever formed at one end with a laterally projecting nose engaging beneath the lug 13, and the spring 12, connecting with the body element 1, spans the upper end of the jaw and has its re- 80 maining end connected with the lever adjacent to the nose. By this spring the lever or latch element when in engagement with the lug 13 is held against the side of the 85 jaw element 9. This catch has attached to it 90 one end of a strap or cord 14 which is carried to and connected with the belly band of the saddle. The cord connects with the lever remote from the nose and obviously a pull upon the cord will tend to spring the 95 lever away from the jaw 9 with the nose as the pivot point. Continued pull on the cord will move the lever to a point where the spring will cease to act to hold it in engagement with the jaw 9, thus allowing 100 the latter to fall.

Both the pins 5 and 7 carry mounted thereon the springs 15, the tendency of which is to turn the tread plate and the arm 4 in the opposite direction from that which is necessary to bring them to normal position. Thus when the jaw 9 is released, these springs tend to throw the tread plate 5' and the arm 4 away from the longer arm of the body member and up in the direction 105 of the shoulder arm thereof.

As will be observed, the catch 13 is re-

leased immediately a strain is imposed on the cable 14 and such a strain would be imposed on the cable were the rider thrown from his mount, as the stirrup would be dragged away from the side of the mount and thereby create a mis-pull. Thereupon the jaw 9 is released and drops or is forced downwardly by the tread plate 5, the springs turning this tread plate and the arm away from the body member, as before described, and thus releasing the rider's foot.

The invention having been described what is new and useful, is:

In a stirrup, an L-shaped body element, 15 an arm having one end hingedly attached to the end of one leg of the body element, a tread plate having one end hingedly attached to the remaining end of the arm, a locking jaw pivotally mounted at the end

of the remaining leg of the body element, 20 the tread plate having a tongue engaging between said jaw and said remaining leg, the jaw lying against the said remaining leg and the tongue resting between the two adjacent the point of pivotal connection, 25 and a spring held latching element carried by the said remaining leg and engaging the jaw to releasably hold the jaw in position for retaining the tread plate in normal position, and a flexible connection between 30 the latch and the girth of the saddle to provide for release of the latch and the jaw upon a definite lateral movement of the stirrup away from the side of the animal being hidden.

In testimony whereof I affix my signature.

FRED GIBBONS.
